UNITED STATES PATENT OFFICE.

LUDWIG GROTE, OF LONDON, ENGLAND, ASSIGNOR OF ONE-HALF TO WILLIAM BEAVAN WATTSON, OF LONDON, ENGLAND.

FUEL BURNER OF THE INJECTOR TYPE.

Application filed June 5, 1923. Serial No. 643,530.

To all whom it may concern:

Be it known that I, LUDWIG GROTE, a citizen of Germany, residing at 177 Mount Pleasant Road, Tottenham, London, England, have invented certain new and useful Improvements Relating to Fuel Burners of the Injector Type, of which the following is a specification.

This invention relates to burners of the injector type and more particularly to such burners of the known types comprising an elongated barrel having any suitable bore for example a tapering bore widening more or less regularly towards the nose end of the burner, and an injector nozzle located coaxially with the said bore in the rear end of said burner so as to project air under pressure along said bore.

It has been proposed to employ burners of this type for burning liquid fuel and means have been proposed to admit such liquid fuel to the bore of said burner at various points. I am not aware however that such burners have ever been employed in burning pulverized solid fuel or that it has ever been proposed so to use them.

This pulverulent solid fuel such as crushed or finely divided coal, lignite, "brown coal", coke, peat, sawdust and the like is cheap and readily obtainable in one form or another and the object (inter alia) of my present invention is to provide an injector burner conforming generally to the aforesaid type but incorporating essential modifications and improvements according to my present invention which render said burner capable of being used at will for burning either pulverulent fuel or liquid fuel, or both simultaneously if desired.

For example I have found that in order to ensure efficient combustion of pulverulent fuel, it is necessary to preheat the air which is injected to the burner and a feature of this invention comprises means attached to or forming part of the body of the burner itself for highly heating the incoming supply of air under pressure for the main injector before injection into and mixture with the fuel in the bore of said burner. Such means for heating the incoming air under pressure comprise an annular jacket surrounding a portion of the body of the burner—advantageously towards the nose end—forming an annular chamber between the jacket and the wall of the burner, the incoming air being

passed through said annular heating chamber and thence conducted to the injector nozzle.

My improved burner may be provided with means for supplying combustible gas thereto or a separate supply of liquid fuel for use when starting from cold for the purpose of heating the burner.

I will now more fully describe my present invention with reference to the accompanying drawings, in which:

Fig. 1 is a longitudinal vertical section of a burner constructed according to this invention.

Fig. 2 is a longitudinal sectional view at right angles to Fig. 1 taken on line 2—2 of Fig. 1, parts being omitted.

Fig. 3 is a cross sectional view on line 3—3 of Fig. 2, looking in the direction of the arrows α .

Fig. 4 is a vertical sectional view taken on line 4—4 of Fig. 3 and showing means for supplying the pulverulent fuel to the burner from below.

Fig. 5 is a local horizontal section of the rear part of the burner illustrating a modified form of injector in which liquid fuel is supplied to an annular passage located around the injector nozzle, whence said fuel is sucked into the enlarged chamber of the bore by injector action.

Fig. 6 is a vertical sectional view of means for supplying the liquid fuel to the burner when the injector illustrated in Fig. 5 is employed.

Referring to Figs. 1 to 4:

The rear part A of the body of the burner is provided with a tapering bore B narrowing rearwardly and then opening out into an enlarged chamber C into which latter the pulverulent fuel is drawn through the tapered openings C¹ and C² by the injector action of air delivered through said chamber C by the nozzle D located in a screw collar D¹ provided with an internal shoulder D² and screwed into the rear wall of the chamber C, the bore of said nozzle D being co-axial with the bore B.

A second part E of the body portion of the burner is screwed down against the boss A¹ of the part A, and this second part E is of such form that an annular space E¹ is left between said part E and the exterior of the forward end of part A and the nozzle E² (Fig. 2) is provided to admit air or and

steam under pressure to said annular space E^1 which terminates forwardly in a circular opening E^3 to the bore B .

A third part F of the body of the burner 5 is screwed over the part E and is arranged to leave between the parts E and F an annular space F^1 terminating forwardly in a circular opening F^2 to the bore B . Combustible gas or liquid hydrocarbons may be 10 supplied through a nozzle F^3 when desired under pressure or otherwise to said space F^1 and thence to the bore B .

A jacket G is screwed on over the part F thereby forming an annular chamber G^1 15 through which the incoming air for injection through nozzle D is passed for the purpose of highly heating such air on its way to said nozzle D . The air under pressure is admitted to the chamber G^1 through the aperture G^2 , passes around the highly heated chamber G^1 and out through aperture G^3 into pipe H provided with a valve H^1 and thence through pipe H^2 to the nozzle D . For convenience in assembling, the pipes H and 20 H^2 are threaded at their abutting ends, and the collar J is screwed thereover to make a good joint.

The part F is provided with a lug K for attachment of the burner to its support or 30 mounting.

If desired liquid fuel may be employed instead of pulverized solid fuel as aforesaid.

Referring more particularly to Fig. 4, by 35 way of example, one arrangement of means for supplying pulverulent fuel to the burner is illustrated.

In this arrangement, depending branch arms L and M are screwed into bosses A^2 , A^3 provided on the body part A and the passages L^1 and M^1 in said branch arms communicate with the chamber C through tapered openings C^1 and C^2 which may if desired be provided with interchangeable nozzles with apertures of different sizes for use 40 according to the granular size of pulverulent fuel employed. Also it is preferable to use a nozzle with a larger aperture for pulverulent fuel than when liquid fuel is employed. Screw-down valves L^2 and M^2 operating in 45 the walls of pipes L and M are provided for the purpose of controlling the supply of fuel through apertures L^1 and M^1 .

Semi-spherical suckers N and O , mounted on the ends of arms L and M respectively, 50 are provided with holes N^1 and O^1 through which the pulverulent fuel (or liquid fuel) is sucked or passed, and nozzles N^2 and O^2 permit a supply of air (which may be heated or not) to be drawn or forced under pressure therethrough to lift or assist in lifting 55 the said fuel to the burner.

The suckers N and O are located respectively in boxes or containers P and Q which are kept substantially full of fuel.

60 The valve rods L^2 and M^2 are shown pro-

vided with passages L^3 and M^3 through which additional supplies of air may be injected if desired. Provision is made for attaching flexible or other suitable tubing to the outer ends of said rods L^2 and M^2 to connect same with the source of supply of air under pressure.

In operation of the embodiment of the invention shown in Figures 1 to 4 inclusive, air under pressure is supplied to the burner being admitted through the aperture G^2 to the chamber G^1 where it is heated to the burner. From there it passes into pipe H , through valve H^1 into pipe H^2 and thence to the nozzle D , the main injector. As shown in Figure 4, pulverulent fuel (or liquid fuel) is supplied through the semi-spherical suckers N and O through pipes L and M to the tapered openings C^1 and C^2 by the action of air delivered through said chamber C by the nozzle D and nozzles N^2 and O^2 , which may assist in the lifting operation in the suckers. Additional air or steam or both under pressure is admitted to the burner through the nozzle E^2 (Figure 2) into the space E , and thence through the circular opening E^3 to the bore B . Combustible gas or liquid hydrocarbons may be supplied to the burner through the nozzle F^3 (Figure 2) into space F^2 , and thence to the bore B .

In the construction illustrated in Figs. 5 and 6:—

The boss R is provided with a forwardly tapering bore into which the air injector nozzle S is screwed leaving an annular passage T which receives liquid fuel through the oppositely disposed openings T^1 and T^2 to which latter the depending conduits U^1 and U^2 respectively (see Fig. 6) are attached. The latter carry at their lower ends spherical suckers W and W^1 provided with holes W^2 and located respectively in suitable liquid fuel containers diagrammatically indicated at X and X^1 .

When starting either type of burner from cold either the said gas or liquid fuel may be used, and when the jacketed portion of the burner is sufficiently hot to insure the heating of the incoming air, the supply of gas or liquid fuel for starting can then be turned off and the burner thereafter run upon the pulverulent, or the liquid fuel or both, as desired.

The parts of the pulverulent and the liquid fuel feeding devices and the relative arrangement of the said parts may be varied largely as desired.

What I claim is:—

1. An injector burner comprising an elongated barrel having a free and unobstructed bore, an air injector nozzle located co-axially with the bore at the rear end thereof, a pre-heating chamber in the wall of the burner for passing therethrough the main supply of air under pressure, means to conduct the

heated air from said chamber to the injector nozzle, fuel inlets in the sides of the bore of the burner towards the rear end thereof and means for supplying additional air under pressure to the bore in advance of the main air supply.

2. An injector burner comprising an elongated barrel with a free and unobstructed bore increasing in cross-sectional area towards the nose end of the burner, an air injector nozzle arranged co-axially with the bore at the rear end thereof, a pre-heating chamber in the wall of the burner for the main air supply for said injector, fuel feeding means entering the sides of the bore towards the rear end thereof and arrangements for supplying additional air to the bore in advance of the main air supply.

3. An injector burner comprising an elongated barrel with a tapering unobstructed bore, an enlargement of the bore at the rear end thereof, an air injector nozzle arranged co-axially with the bore to the rear wall of said enlargement, fuel feeding conduits entering the sides of said enlargement, an air heating chamber in the wall of the burner towards the front end thereof, means to admit air under pressure to said chamber and to conduct the heated air from said chamber to the said injector nozzle and means for supplying additional air to the bore of the burner in advance of the main air supply.

4. An injector burner comprising an elongated barrel with a tapering unobstructed

bore, an enlargement of the bore at the rear end thereof, an injector nozzle arranged co-axially with the bore in the rear wall of said enlargement, fuel conduits entering said enlargement, an air heating chamber in the wall of the burner towards the front end thereof, means to admit air under pressure to said chamber and to conduct the heated air from said chamber to the said injector nozzle, means for supplying additional air under pressure to the bore of the burner, and means for supplying liquid or gaseous fuel to the bore of the burner in advance of the main fuel supply.

5. An injector burner comprising an elongated barrel with a tapering unobstructed bore, having an enlargement at the rear end thereof, an injector nozzle co-axial with the bore in the rear wall of said enlargement, fuel conduits entering said enlargement and depending into receptacles for the fuel, induction devices on the lower ends of said conduits, valves controlling the inlet orifices from said conduits to the enlargement of the bore, a heating chamber in the wall of the burner towards the nose end thereof for preheating the incoming main air supply under pressure, means to conduct the heated air from said chamber to the injector nozzle, inlets to the bore for additional air and means for supplying fuel to the bore in advance of the main fuel supply.

LUDWIG GROTE.
